Rec'd.

UNITED STATES PATENT OFFICE.

JOHN KNELL, OF AURORA, ILLINOIS, ASSIGNOR TO ALL-STEEL-EQUIP COMPANY, A CORPORATION OF ILLINOIS.

LOCKER HINGE.

Application filed June 17, 1925. Serial No. 37,669.

To all whom it may concern:

Be it known that I, JOHN KNELL, a citizen of the United States, and resident of Aurora, county of Kane, and State of Illinois, have invented certain new and useful improvements in Locker Hinges, of which the following is a specification, and which is illustrated in the accompanying drawings, forming a part thereof.

10 This invention relates to cabinets, and more particularly to metal lockers and hinges therefor.

One of the objects of the invention is the provision of simple mechanism for hinging a door to a metal locker in such a manner that the weight of the door will be properly supported and the sagging of the same reduced to a minimum.

Another object of the invention is the provision of a new and improved hinge mechanism for hinging a door to a locker that is cheap to manufacture, easily assembled, efficient in operation, composed of a minimum number of parts, simple and rugged in construction, and that is not likely to become broken, distorted or get out of order.

Other and further objects and advantages of the invention will appear from the following description taken in connection with the accompanying drawings, in which—

Fig. 1 is a front elevation of a locker showing the invention in position thereon;

Fig. 2 is a vertical section through the hinge;

Fig. 3 is a vertical section on line 3—3 of Fig. 2;

Fig. 4 is a vertical section on line 4—4 of Fig. 3;

Fig. 5 is a horizontal section on line 5—5 of Fig. 3;

Fig. 6 is an elevation of the door, the view being taken from the hinged edge thereof, parts broken away;

Fig. 7 is a perspective view of the pintle and its attaching strip;

Fig. 8 is a perspective view of the retaining plate;

Fig. 9 is a cross-section of a portion of the door post and door, of a modified form of the device, showing the hinge partly assembled;

Fig. 10 is a section on line 10—10 of Fig. 11;

Fig. 11 is a section on line 11—11 of Fig. 10;

Fig. 12 is an edge elevation of a portion of the door showing the slot therein;

Fig. 13 is a cross-section of a door and door post showing a still further modified form of the device, with the parts in partly assembled relation;

Fig. 14 is a section on line 14—14 of Fig. 15, showing a still further modified form of the device;

Fig. 15 is a section on line 15—15 of Fig. 14, with parts broken away; and

Fig. 16 is a section on line 16—16 of Fig. 14, with parts broken away.

On the drawing the reference character 10 designates a locker or cabinet which is preferably, though not necessarily, all metal and is provided with a door opening 11 which is adapted to be closed by a door or closure as is usual in such constructions.

The plate 12 forming the door part is preferably of sheet metal and its edge is provided with a flange 13 which may be return bent as at 14 for reinforcing the flange.

The door post or jamb 15 to which the door is hinged may be in the form of an angle bar having flanges 16 and 17 forming one of the corners of the locker. The adjacent side panel 18 of the locker is attached to the flange 16 and the flange 17 is adapted to support the door in a manner that will now be described.

The corner formed by the plate or panel 12 and the flange 13 is cut away to form a slot 19 as best shown in Fig. 6. The slot 19 is extended both above and below in the flange 13 as at 21 and 22, see Fig. 6, to accommodate the entrance of the hinge pintle as will presently appear.

The corners of the door adjacent to the upper and lower ends of the slot 19 are pressed outward to form sockets or recesses 23 and 24 for the reception of the upper and lower ends of the hinge pintle 25. The hinge pintles are secured in any suitable manner to the door post. As shown more particularly in Fig. 7 a strap 26 is folded about the pintle 25 and is secured by bolts 27 to the flange 17. The eye 28 formed by the folded portion of the strap is offset so that the door or panel 12 will be flush with the flange 17 when the parts are assembled and the door closed.

In assembling the device the loop portions 28 with the pintle 25 is inserted through the slots 19, 21 and 22 and the pintle seated in the sockets or recesses 23 and 24. A retainer plate 30 provided with flanges 32 spaced apart is rigidly secured to the flange 13 in any suitable manner as by means of the bolt 33. The flanges 32 engage the ends of the pintle and hold the same in the sockets 10 or recesses 23 and 24.

The width of the strap 26 is substantially the same as the distance between the sockets 23 and 24, whereby a close fit is made and the door supported from the strap 26 by the 15 shoulders 31 formed by the sockets 23 and integral with the door panel. This is considered an important feature of the invention because this arrangement provides means for supporting the door with a minimum 20 number of parts, and the sockets 23 and 24 and the shoulder 31 being integral with the door construction insures against the rocking or sagging of the door due to its use.

25 The form of the device shown in Figs. 9, 10, 11 and 12 differs from that shown in Figs. 1 to 8 in that the slot 34 for the reception of the hinge strap 26 of the hinge, see Figs. 11 and 12, does not 30 have an extension at each end thereof, corresponding to the extension slots 21 and 22 in Fig. 6. In assembling this form of the hinge the eye of the hinge strap 26 is passed through the slot 34 adjacent to the side 35 edge 35 of the slot as shown in Fig. 9, and the pintle placed in the eye of the strap, after which the strap and pintle are slid back until the pintle engages the recesses 23 and 24. The retainer plate 30 is then applied 40 to hold the pintle in position as in the previous figures, and the strap is rigidly connected to the door post 15 in the same manner as described above. If desired, the strap may be rigidly connected to the door post as by means of the bolts 27 as shown in 45 Fig. 10, or by spot welding the same as at 36 in Fig. 13, before the same is inserted in the slot 34. In this event, the strap being rigidly attached to the door post, is stationary 50 and the door containing the slot 34 is manipulated to pass the slot therein over the strap, as clearly shown in Fig. 13. After the pin has been inserted and the door manipulated to seat the pintle in the recesses 23, the retainer plate 30 is attached to hold the 55 pintle in position as in the structures previously disclosed.

60 The remaining parts of the construction are identical with the corresponding parts in Figs. 1 to 8 and are indicated by the same reference characters. A reiteration of their description is deemed unnecessary.

In the form of the device shown in Figs. 65 14, 15 and 16 the retainer plate 30 is dispensed with, ears or tabs 37 and 38 integral

with the flange 13 of the door being bent about the upper and lower ends respectively of the pintle 25, for retaining the same in position in the recesses. The ears or tabs 37 and 38 are formed in the following manner. The slot 41, which corresponds to the slot 34 in Fig. 12, for the reception of the loop portion 26 of the hinge, is shown as extending between the dotted lines 42, 42 in Fig. 16. An angular 70 slit is made above and below the slot 41 which partially severs the portions 37 and 38. These portions are bent laterally about the ends of the pintle to hold the same in the recesses, as shown in Fig. 14. 75

80 While in the embodiment of the invention shown, the sockets 23 and 24 are on the door construction, it is understood the arrangement may be otherwise, the construction shown on the drawing being by way of 85 example only.

85 In both forms of the device shown in Figs. 9 to 16 inclusive, if desired, the hinge pintle may be rigidly connected to the hinge strap, after which the strap may be passed 90 through the slot in the door from the inside before it is connected to the door post.

95 It is thought from the foregoing taken in connection with the accompanying drawings that the construction and operation of 100 my device will be apparent to those skilled in the art, and that various changes in size, shape, proportion and details of construction may be made without departing from the spirit and scope of the appended claims.

105 Without limiting myself to the construction and arrangement shown, I claim:—

1. In combination, a locker having an opening in one wall thereof, a reinforcing angle bar along one side of said opening, a closure for said opening comprising a sheet metal plate having one edge bent to form a flange, the apex of the angle formed by said angle bar having a portion cut away to form a slot, and portions adjacent 110 said slot pressed out to form sockets, a strap having a pintle for engaging said sockets, means for attaching said strap to said angle bar, and means for holding said pintle in 115 said sockets.

2. In combination, a door post, a door supporting strap rigid therewith, a door panel provided with a flange, sockets at the apex of the angle formed by the flange and panel, a pintle carried by said strap for engaging said sockets, and means for holding the ends of said pintle in said 120 sockets.

3. A sheet metal door comprising a body portion, a flange along one side of said body portion, the apex of the angle formed by the flange and body portion being provided with a slot, and sockets formed by pressing the metal outward at said angle above and 125 below said slot. 130

4. In combination, a sheet metal door comprising a body portion and a flange along one side edge of said body portion, integral sockets on said flange and body portion, a door post, a hinge pintle for engaging said sockets, and means for rigidly connecting said pintle to said post.
5. In combination, a door post, a hinge pintle mounted on said post, a door, sockets carried by said door for engaging said pintle, and a retaining member detachably connected to said door, said member being provided with means for retaining said pintle in said sockets.
6. In combination, a door having sockets and shoulders integral therewith, a door supporting member, hinge pintles for engaging said sockets, and means for supporting said pintles from said support, said means engaging said shoulders for supporting said door.
7. In a locker provided with a door supporting member, a door comprising a sheet metal body portion having an integral flange and provided with sockets forming shoulders, hinge pintles engaging said sockets, straps looped about said pintles and engaging certain of said shoulders for supporting said door, and means detachably connected to said flange for holding said pintles in said sockets.
8. A door for lockers and the like, comprising a body of sheet metal, a flange along one edge thereof, the corner formed by the flange and body portion being slotted and having a socket above and below each slot, and a retaining member secured to said flange and having a lateral extension opposite each socket for retaining the end of a pintle therein.
9. In a locker, a door post member, a door member, a strap on one of said members, said strap having an eye, a hinge pintle in said eye, the other member being provided with a slot for receiving said eye and having a recess above and below said slot for receiving the ends of said pintle, and a retaining member having laterally extending lugs for engaging said pintle for holding the same in said recesses.
10. In a locker, a door supporting member, a sheet metal door having one edge provided with a flange terminating in a return bent portion, said flange being provided with a slot, and recesses adjacent to said slot, a hinge member extending through said slot, means for connecting said hinge member to said door supporting member, and means including a pintle engaging said recesses for hingedly connecting said hinge member to said door.

In testimony whereof I affix my signature.

JOHN KNELL.
